UNITED STATES PATENT OFFICE.

GEORGE E. BALES, OF WALLA WALLA, WASHINGTON TERRITORY.

SNAP-HOOK AND BUCKLE.

SPECIFICATION forming part of Letters Patent No. 234,738, dated November 23, 1880.

Application filed October 6, 1880. (No model.)

To all whom it may concern:

Be it known that I, GEORGE E. BALES, of Walla Walla, Walla Walla county, Washington Territory, have invented a new and Improved Combined Snap-Hook and Buckle, of which the following is a specification.

The object of this invention is to provide a more convenient and secure device for breast-straps, hitching and other straps or lines on which snap-hooks are commonly used.

Figure 1 is a longitudinal side elevation of the device. Fig. 2 is a plan of the same, and Fig. 3 is a perspective view of the same, with parts broken away to show other parts.

Similar letters of reference indicate corresponding parts.

In the drawings, A represents the snap-hook, having its shank reduced so as to form shoulders *a a*, having the extremity of its hooked point rabbeted on one side, as shown at *b*, and having the end of its shank drawn down, as shown at *c*, for the purpose of making a suitable joint at the point of connection with the buckle B. A' is a segmental locking-piece, secured by its rings *d d* on the reduced portion of the shank of the snap-hook A. Between the shoulders *a a* and *f* is a spiral spring, having one end secured to the shank of the hook A, while the free end of said spring *f* bears against the side of the locking-piece A', as shown in Fig. 1, whereby the lateral rotation of the said piece A' is restricted, and whereby it is closed against the rabbeted end *b* of the snap-hook A and retained in that locked position, so that the outer face of the hook and locking-piece A A' shall be flush and even with each other.

To the drawn-down or flattened end *c* of the

40 snap-hook A is fixed a buckle, B, projecting in a straight line therefrom, said buckle having a horizontal, square, single-looped frame, *g*, provided with tongue *h* and a loop, *i*, that projects upward at right angles from the rear of said frame *g*.

45 C represents a hitching-strap, to which the combined snap-hook and buckle is designed to be secured, as shown in the drawings, wherein said strap C is passed through the loop of frame *g*, and is secured by the tongue *h* passing through a suitable hole, *k*, in said strap, 50 and the end of said strap C is then inserted into the loop *i*, and thereby held in place.

55 This snap-hook A is more easily unsnapped and less liable to become clogged with ice or mud than those now in use, and the buckle B 60 obviates the necessity of sewing billets on the hitching-straps, or on any straps or lines on which a snap-hook is used, and also saves the labor of sewing on the snap-hook itself, and makes a stronger connection between the strap C and snap-hook A.

Having thus described my invention, I claim as new and desire to secure by Letters Patent—

65 In a snap-hook, the combination, with the hook A, having side rabbet at its point and shoulders *a a* on its shank, of the locking-piece A', having rings *d d*, and the spiral spring *f*, secured at one end to the hook-shank and bearing with the other against the side of said locking-piece, as and for the purpose specified.

70 GEORGE EDWARD BALES.
